LIQUID DETERGENT COMPOSITION

William C. Krumrei, Springdale, Ohio, assignor to The Procter & Gamble Company, Cincinnati, Ohio, a corporation of Ohio

No Drawing. Application June 29, 1956
Serial No. 594,676

7 Claims. (Cl. 252—138)

This invention is directed to the provision of liquid 15 heavy duty detergent compositions and particularly compositions which contain large amounts of pyro- or tri- polyphosphate but which do not tarnish or corrode aluminum to an objectionable degree.

The corrosion inhibitor most effective in inhibiting corrosion of aluminum by alkaline phosphates is silicate of soda. In the compositions of the prior art, the addition of silicate of soda to an aqueous solution of the anionic synthetic detergents and an alkaline phosphate caused a separation, cloudiness or "livering." This is described in U. S. Letters Patent 2,618,607, issued November 18, 1952, to Herbert L. Sanders.

Most anionic synthetic detergents are not, unassisted, completely soluble in aqueous phosphate solutions of a concentration of 20% or more, even in the absence of silicate. The anionics "salt out," forming a gummy layer at the top of the solution. Complete solution of anionic synthetic detergent in such phosphate solutions can be achieved, however, with a solubilizer, usually a sodium salt of the sulfonates of benzene or methyl substituted benzene. If one adds silicate of soda, in amounts adequate to inhibit corrosion of aluminum during the use of the composition in cleansing operations, to those previously known phosphate solutions into which an anionic synthetic detergent has been thus solubilized, the silicate will not dissolve completely, but forms a gelatinous mass.

I have found that a specific anionic synthetic detergent in aqueous liquid heavy duty detergent formulations has the property of solubilizing silicate of soda in amounts adequate to inhibit corrosion by phosphates. The specific anionic synthetic detergent is a water soluble alkali metal salt of alkyl glyceryl ether sulfonate in which the alkyl radical is derived at least 50% from alcohols of 10 to 14 carbon atoms.

These alkyl glyceryl ether sulfonates have an additional advantage, they inhibit the redeposition of soil, thus eliminating the need for sodium carboxymethyl cellulose. The carboxymethyl cellulose does not dissolve completely in aqueous detergent solutions thus imparting a murky look to the solution.

A typical composition embodying the discovery herein described will contain from about 6% to about 14% of alkali metal salts of alkyl glyceryl ether sulfonate, 12% to 27% of potassium pyrophosphate, or potassium tri- polyphosphate, 2% to 6% of ethyl or isopropyl alcohol, or diethylene glycol monobutyl ether, 3.5% to 6% of silicate of soda (solids basis) of $\text{SiO}_2:\text{Na}_2\text{O}$ ratio of 1.6:1 to 2.6:1, 3.0% to 8% of a solubilizing agent, and water to make 100%. This produces a clear solution at room temperature, and remains clear down to about 50° F.

2

The aforesaid salts of the alkyl glyceryl ether sulfonate are made by reacting fatty alcohol mixtures containing at least 50% of alcohols of 10 to 14 carbon atoms with epichlorohydrin and by reacting the alkyl chloroglyceryl ethers so formed with sodium or potassium sulfites.

The alkyl glyceryl ether sulfonate used in the examples contains about 15% of diglyceryl ether sulfonates. This is only because of the ease of manufacturing this species. The invention may be carried out with alkyl glyceryl ether sulfonates, where the alkyl is at least 50% radicals of alcohols of 10 to 14 carbons, with only monoglyceryl radicals present or with up to about 30% of diglyceryl radicals present. The term alkyl glyceryl ether sulfonate as used herein means any and all of the alkyl glyceryl ether sulfonates from those containing no diglyceryl radicals to those containing up to 30% diglyceryl radicals.

Instead of the fatty alcohols used to prepare the alkyl glyceryl ether sulfonate there may be used the alcohols prepared by the "oxo" reaction from straight chain olefins. These should meet the same qualifications as to chain length as the fatty alcohols, that is, these should contain at least 50% of alcohols of 10 to 14 carbons.

25 A number of solubilizing agents are useful in effecting complete solution of synthetic detergents in relatively concentrated electrolyte systems. Trialkyl phosphates, where the alkyl is of low molecular weight, such as tri- amyl phosphate, or other trialkyl phosphates where the sum of the carbons in the alkyl groups are not more than 15 are effective. The alkali metal salts of various organic sulfonates have been used for their solubilizing properties. Petroleum sulfonate salts, salts of benzene sulfonate and methyl substituted benzene sulfonate are among the best of these. The manner in which the anionics solubilize is presented in Schwartz and Perry, "Surface Active Agents," page 307 et seq., Interscience Publishers, New York, 1949.

Generically speaking the solubilizers found useful in 40 the present invention are anionic surface active materials, the molecules of which contain both a hydrophobic hydrocarbon portion and a hydrophilic portion. The hydrophobic hydrocarbon portion of the molecule, if of straight chain configuration, may contain from one to 45 three separate alkyl groups each containing not more than 5 carbon atoms. If of cyclic configuration, the hydrophobic hydrocarbon portion of the molecule may contain only one alkyl-substituted or unsubstituted cyclic group containing a total of not more than 8 carbon atoms. The hydrophilic portion of the molecule may be either the water-soluble salt of a sulfonic acid radical (sulfonate) or a phosphate. It is to be understood that wherever hereinafter and in the claims the term "anionic 50 solubilizer" appears a material coming within the scope of the above definition is intended.

The solubilizer I prefer is sodium toluene sulfonate. Sodium benzene sulfonate and sodium xylene sulfonate are also effective but require slightly larger amounts to effect blending. Example I and the explanation following show the steps needed to completely blend the ingredients into a clear solution.

Example I

The anionic used was alkyl glyceryl ether potassium sulfonate in which the alkyl was derived from middle

cut coconut alcohols containing 66% dodecanol. The epichlorohydrin used in making the chloroether was in the molar ratio of 1.15 to the fatty alcohol. This excess of epichlorohydrin will produce glyceryl chloroethers with about 15% of the glyceryl chloroethers present as diglyceryl dichloroethers. This alkyl ether mixture was reacted with potassium sulfite to produce the alkyl glyceryl ether potassium sulfonate. From this synthetic sulfonate, a detergent composition was prepared as follows, all parts by weight.

	Parts by wt.
Water heated to about 135° F. and this temperature maintained	51
Potassium alkyl glyceryl ether sulfonate dissolved in the water	12
Potassium pyrophosphate is added to the above solution	20
Sodium silicate solution containing 4 parts of silicate solids of $\text{SiO}_2/\text{Na}_2\text{O}$ ratio of 2:1 is added	9

On standing, part of the alkyl glyceryl ether sulfonate tends to salt out and forms a viscous top layer and some of the phosphate settles out. After cooling, with adequate agitation, as by shaking a can or bottle containing this detergent, a liquid heavy duty detergent of adequate cleansing power can be achieved. Washing solutions prepared from this detergent do not attack aluminum to an objectionable degree. However, they would not be considered satisfactory detergents in the scope of this invention, because of their tendency to separate, as set forth.

Upon admixture of 4 parts of ethyl alcohol, as an assistant solubilizer, with the above composition at a moderately warm temperature, say 90° F., the alkyl glyceryl ether sulfonate is dissolved. This preparation upon standing at room temperature tends to resolve itself into two clear layers. With adequate agitation, as by shaking the can or bottle, this two phase mixture can be used as a heavy duty detergent to inhibit corrosion of aluminum by washing solutions prepared from the detergent. This two phase composition is a heavy duty liquid detergent base of great utility in that it can be converted into a marketable detergent by one of several methods. Our preferred method is to add a solubilizer, 40 converting the mixture to a single phase liquid. The two phase base can be converted to a reasonably permanent emulsion by the addition of emulsifying agents or by the addition of finely divided solids such as amorphous silica or clay of the bentonite type. Considered as a detergent base, this two phase liquid detergent is within the scope of the present invention.

The assistant solubilizer is normally added to the mixture right after the alkyl glyceryl sulfonate, to reduce viscosity for mixing purposes. It may be added at any time before the solubilizer is added and be effective as a solubilizing assistant. It appears that the addition of alcohol or other assistant solubilizer causes a resolution of the composition into two clear phases, the top layer containing most of the anionic synthetic detergent in solution. The removal of this detergent from the water in the lower layer enables this layer to completely dissolve the phosphate.

The addition of the solubilizer, in this example, 4 parts of sodium toluene sulfonate, caused the layers to dissolve in one another and become a single phase. This phenomenon takes place only when the anionic comprises a minimum of at least 6% of alkyl glyceryl ether sulfonate. It is in this fashion that the alkyl glyceryl ether sulfonate makes possible the preparation of a single phase heavy duty liquid detergent containing an effective amount of silicate.

Example II

These materials were of the same character as used in Example I.

	Parts by Wt.
Potassium alkyl glyceryl ether sulfonate ¹	12
Water at 135° F., this temperature was maintained	51
Potassium pyrophosphate was added to the above solution	20
Ethyl alcohol was used to control viscosity and facilitate blending	4
Sodium silicate solution containing 4 parts of silicate solids of $\text{SiO}_2/\text{Na}_2\text{O}$ ratio of 2:1 was added	9
Sodium toluene sulfonate was added and the mixture stirred well	4

¹ This was accompanied by a small amount (less than 2 parts) of potassium chloride which is not considered in the parts by weight.

This was a clear liquid at room temperature and had good heavy duty detergent properties and did not corrode aluminum significantly. Potassium tripolyphosphate may be used in place of potassium pyrophosphate in this composition.

Example III

This composition contained the following—all parts by weight.

	Parts by Wt.
Potassium alkyl glyceryl ether sulfonate	10
Potassium pyrophosphate	30
Sodium silicate solids	4
Sodium toluene sulfonate	4
Ethyl alcohol	4
Water	44
Inorganic salts from sulfonation, tarnish inhibitors, coloring material, perfume	4

These materials, except for the tarnish inhibitors, coloring material, and perfume, were the same as shown in Example I, and were made into a clear solution in the same manner. The pyrophosphate in this example is about the upper limit of solubility at room temperature in this preparation, which shows how a proper choice of materials enables a concentrated detergent to be prepared. This preparation did not corrode aluminum significantly. The ethyl alcohol may be replaced by isopropanol in this example with substantially equal results.

Example IV

At the 10% level of synthetic detergent 10% sodium alkyl glyceryl ether sulfonate may be used in place of the potassium salt. The alkyl is the same as used in potassium glyceryl ether sulfonate. The preparation has the following composition—all parts by weight.

	Parts by Wt.
Sodium alkyl glyceryl ether sulfonate. The alkyl glyceryl ether sulfonate the same as in Example I, the sulfite salts used in sulfonation being sodium salts	10
Potassium pyrophosphate	30
Ethyl alcohol	4
Sodium toluene sulfonate	4
Sodium silicate solids, $\text{SiO}_2/\text{Na}_2\text{O}$ ratio of 2:0:1	4
Water	44
Inorganic salts from sulfonation, tarnish inhibitors, coloring matter and perfume	4

This was blended together as shown in Example II. When added to water in detergent concentrations it had good heavy duty detergent properties and did not corrode aluminum significantly. The ethyl alcohol in this formula may be replaced by diethylene glycol monobutyl ether with substantially equal results.

The above examples show that alkyl glyceryl ether sulfonate will solubilize silicate in phosphate solutions and may be used to prepare effective liquid heavy duty synthetic detergents.

If anionic synthetic detergents other than alkyl glyceryl ether sulfonate are used as the sole anionic in the for-

mulations of the above examples, a clear single phase solution is not attained. If, for instance, alkyl benzene sulfonate, where the alkyl is polypropylene averaging about 12 carbons, is used, the addition of alcohol causes two clear layers to form, but they will not blend into a single phase solution upon the addition of a solubilizer and stirring. If an alkyl sulfate, where the alkyl contains at least 50% of radicals from alcohols of 10 to 14 carbon atoms is used, the anionic will not stay in solution but salts out due to insolubility of the potassium alkyl sulfate which can be formed by reaction with the potassium phosphate.

A convenient test for clarity may be made by placing the preparation in a test tube 20 mm. diameter and 150 mm. long and holding for five days at some selected temperature below room temperature, 60° F., 50° F., and 40° F., are commonly used.

In this test highly satisfactory compositions will not cause the alkyl glyceryl ether sulfonate to salt in a viscous or jell-like layer at the top, nor separate a precipitate of phosphate or silicate at the bottom of the tube.

Ordinary visual observation in good light, as looking toward a window, is used to determine the state of the preparation. Compositions not highly satisfactory by very low temperature test can be used as detergents at room temperature—say 70° F.—if they become clear and free from separated material at this temperature.

The silicate and the alkali toluene sulfonate preferably are added as the sodium salts. The presence of at least as much sodium ions as are added with these compounds is desirable for improved solubility.

It will be understood that the coloring matter and tarnish inhibitors may be added at any convenient point in the mixing of the composition, and that perfume may be added after the composition has been prepared and cooled.

The formulas may be varied somewhat from those given in the examples. All of the examples show the use of fatty alcohol containing at least 50% of dodecyl alcohol as the alkyl in the alkyl glyceryl ether sulfonate. For good sudsing properties the use of this alkyl glyceryl ether sulfonate is essential. At the maximum concentrations in solution, the sum of the alkyl glyceryl ether sulfonate and the phosphate will be approximately constant. Each of these components seems to "use up" about the same amount of solubilizing power. Hence, if the percent of phosphate is raised, the alkyl glyceryl ether sulfonate will have to be lowered by about the same amount, this, of course, being in solutions of maximum concentration at room temperatures. The sum of these two ingredients will be in the range of not over about 40% in concentrated solutions. Totaling up the other ingredients, it will be evident that not less than about 40 parts of water will be required to make the total parts equal 100. Considering the more dilute compositions, it will be seen that 75 parts of water is the maximum that will be required to total 100 parts.

The blending agent or solubilizer should be from about 3.0% to about 8%, less than 3% being ineffective and more than 8% adding nothing to the performance.

Either potassium tripolyphosphate or potassium pyrophosphate, or mixtures of the two may be used up to the limit of solubility at room temperatures in these compositions.

Our preferred composition contains about 20% pyrophosphate because of the greater solubility and stability of this phosphate.

The alcohols, ethanol or isopropanol used to solubilize the anionic synthetic detergent may be used from about 2% to about 6%. Diethylene glycol monobutyl ether can be substituted for the alcohol as an assistant solu-

bilizer. Less than 2% alcohol is undesirable from the point of viscosity and freeze recovery, and more than 6% causes a tendency to separation into two phases.

In the compositions containing about 20 parts of potassium pyrophosphate in about 50 parts of water, the amount of alkyl glyceryl sulfonate must be at least 6% to solubilize the silicate in effective amounts. The amount of alkyl glyceryl ether sulfonate may go as high as 14%, but at the expense of clarity at low temperatures.

10 What is claimed is:

1. A single phase liquid heavy duty detergent composition consisting essentially of, in parts by weight, from 6 to 14 parts of salts of alkyl glyceryl ether sulfonate of which the cation is an alkali metal, at least 50% of the alkyl groups of the said alkyl glyceryl ether sulfonate being derived from alcohols having from 10 to 14 carbon atoms, from a minimum of 12 parts to a maximum of the limit of solubility at room temperature of a phosphate selected from the group consisting of potassium pyrophosphate, potassium tripolyphosphate and mixtures thereof, 3.5 to 6 parts of sodium silicate solids having a $\text{SiO}_2/\text{Na}_2\text{O}$ ratio of 1.6:1 to 2.6:1, 3 to 8 parts of an anionic solubilizer selected from the group consisting of trialkyl phosphates, wherein each of the alkyl groups contains not more than 5 carbon atoms, the alkali metal salts of benzene sulfonate, the alkali metal salts of toluene sulfonate and the alkali metal salts of xylene sulfonate, 2 to 6 parts of an assistant solubilizer selected from the group consisting of ethyl alcohol, isopropyl alcohol and diethylene glycol monobutyl ether, and not less than 40 parts and not more than 75 parts of water.

2. The detergent composition of claim 1 wherein the phosphate is potassium pyrophosphate.

3. The detergent composition of claim 1 wherein the assistant solubilizer is ethyl alcohol.

4. Detergent composition of claim 1 wherein the assistant solubilizer is isopropyl alcohol.

5. A single phase liquid heavy-duty detergent composition consisting essentially of, in parts by weight, 6 to 14 parts of salts of alkyl glyceryl ether sulfonate of which the cation is an alkali metal, at least 50% of the alkyl groups of the said alkyl glyceryl ether sulfonate being derived from alcohols having from 10 to 14 carbon atoms, 12 to 27 parts of a phosphate selected from the group consisting of potassium pyrophosphate, potassium tripolyphosphate and mixtures thereof, 3.5 to 6 parts of sodium silicate solids having a $\text{SiO}_2/\text{Na}_2\text{O}$ ratio of 1.6:1 to 2.6:1, 3 to 8 parts of an anionic solubilizer selected from the group consisting of trialkyl phosphates wherein each of the alkyl groups contain not more than 5 carbon atoms, the alkali metal salts of benzene sulfonate, the alkali metal salts of toluene sulfonate and the alkali metal salts of xylene sulfonate, 2 to 6 parts of an assistant solubilizer selected from the group consisting of ethyl alcohol, isopropyl alcohol and diethylene glycol monobutyl ether, sufficient water being present in the composition to bring the total of all components to 100 parts.

6. The detergent composition of claim 5 wherein the phosphate is potassium pyrophosphate.

7. The detergent composition of claim 6 wherein the phosphate is present in the composition in an amount about 20 parts by weight.
